SUCTION CLEANING APPARATUS

Charles H. Taylor, Springfield, Mass., assignor to Westinghouse Electric & Manufacturing Company, East Pittsburgh, Pa., a corporation of Pennsylvania

Application January 23, 1942, Serial No. 427,850

9 Claims. (Cl. 15—179)

This invention relates to improvements in brush rolls or rotors and while it is applicable to many forms and kinds of brush rolls and rotors it is particularly applicable to brush rolls or rotors that are used within the nozzle of a suction cleaner.

An object of this invention is to provide an improved brush roll or rotor for a suction cleaner.

Another object is to provide an improved brush roll or rotor which is of simple construction and which may be economically manufactured.

A still further object is to provide an improved plastic brush roll or rotor for a suction cleaner wherein provision is made to allow parts of the brush roll to move freely relative to other parts when they expand or contract unequally, particularly when the plastic roll members shrink in the initial molding of the same.

These and other objects are effected by the invention as will be apparent from the following description and claims taken in connection with the accompanying drawing forming a part of this application, in which:

Fig. 1 is a side view of a brush roll constructed in accordance with this invention, with parts broken away;

Fig. 2 is a partial enlarged side view with parts broken away;

Figs. 3, 4, and 5 are sections taken along lines III—III, IV—IV, and V—V, respectively, of Fig. 2; and,

Fig. 6 is a partial side view of a modification.

Referring to Figs. 1 to 5 in particular, a brush roll or rotor constructed in accordance with a preferred embodiment of this invention is indicated generally by the reference character 10. The brush roll or rotor includes a tubular member or core 11 having a pulley 12 thereon by means of which the brush roll or rotor is rotated by a belt (not shown), and roll members 13 having tufts of bristles 14 mounted spirally thereon.

The tubular member 11 may be made of metal or any other suitable material and the pulley 12, which may be made of metal or any other suitable material, is pressed thereon. The member 11 is knurled as indicated at 15. These knurls slightly bite into the pulley 12 and assist in preventing it from rotating on the member 11. The member 11 has a smooth surface, except for, circumferential grooves 19 and axial grooves 20 provided therein near its respective ends.

The roll members 13 are preferably made of plastic material. However, it will be understood that they may be made of any satisfactory material. These portions are molded under heat

and pressure or cast onto the tubular member 11, and some of the material flows into the circumferential grooves 19 and some flows into the axial grooves 20. The circumferential grooves 19 coat with the material therein and provide a lock which prevents the portions of the roll members 13 that are adjacent the grooves 19 from moving axially on the tubular member 11. The axial grooves 20 also coat with the material therein and provide a lock which prevents the roll members 13 from rotating on the tubular member 11.

During the molding of the plastic roll members 13, the plastic material is heated to a relatively high temperature. After the initial molding the plastic material cools and contracts more rapidly and to a greater extent than the tubular member 11, and the portions of the members 13 that are not locked to the tubular member 11 move axially of the member 11 toward the grooves 19. The smooth surface of the tubular member 11 does not make a very good bond with the plastic material used in the roll members 13. This permits the portions of the members 13, that are not locked to the tubular member 11, by the grooves 19 and 20, to slide along the tubular member 11 without setting up objectional stresses in either the tubular member 11 or the plastic roll members 13. During the cooling of the roll members 13 they contract far enough to provide clearance spaces 23 and 24 between the pulley 12 and the adjacent ends of the roll members 13. These clearance spaces permit subsequent expansion of the plastic roll members 13 without pressing against the pulley 12, which action might distort the tubular member 11 and set up abnormal stresses in the plastic roll members 13 that might crack or warp the same, or injure the bond between the roll members 13 and the tubular member 11 where they are locked together. Because the plastic roll members 13 never get as hot in operation as the initial molding temperature, consequently, they will never expand back to their original size so as to contact the pulley 12.

It is also desirable to have clearance spaces between the ends of the roll members 13 and the pulley 12 to prevent cracking of the roll members 13 when rotary motion is applied to the pulley in case the pulley becomes slightly loose on the tubular member 11.

It will be noted that the pulley 12 has a smaller diameter than the roll members 13 and the end portions 21 of the roll members extend over the edges of the pulley 12 and serve as guides to prevent the belt from running off the

pulley. This overlapping of the roll members 13 onto the pulley 12 also serves to cover from sight the clearance spaces between the roll members and the pulley.

The outer ends 25 of the roll members 13 are recessed at 26 to receive ball bearings, indicated generally by the reference character 27, and a washer 28. The recesses 26 may be moulded into the roll members or they may be formed therein by some satisfactory method after the roll members have been molded onto the tubular member 11. A shaft 29 extends through the tubular member 11 and projects from the end thereof to provide portions 30 by means of which the brush roll or rotor is mounted in the nozzle of a suction cleaner. The shaft 29 is screwthreaded near its respective ends and plates 31 are screwed thereon to hold the bearings 27 and the washers 28 in place in the recesses 26. When mounted in the nozzle of a suction cleaner, the brush roll 10 rotates about the shaft 29. The projecting portions 30 of the shaft have a cross section, preferably other than round, to facilitate mounting the shaft in the nozzle of a suction cleaner so that the shaft will not rotate when rotary motion is applied to the pulley 12. A clearance space 32 is also provided, by any suitable method, between the inner end of the recess 26 and the bearing 27 and a clearance space 33 is likewise provided between the ends 25 of the roll members 13 and the plates 31. These clearance spaces 32 and 33 permit end portions 25 of the roll members 13 to expand without binding against the plates 31 and bearings 27.

In Figs. 2 and 4, a method of attaching a tuft of bristles 14, which includes a plurality of bristles bent to U-shape, to the brush roll 10 is illustrated. To attach the bristles in this manner, a hole 37 is drilled into the plastic member 13 and a hole 38 is drilled into the tubular member 11 so as to line up with the hole 37 in the plastic member. A U-shaped staple 34 having legs 35 and 36 is hooked into the bottom of the U formed by bending the bristles and the staple and the end of the bristles having the U-bend therein are inserted into the hole 37 so that the staple projects through the hole 38 into the interior of the tubular member 11. The bristles are held in position in the hole 37 by spreading the legs 35 and 36 of the staple against the inside of the tubular member 11, as shown in Fig. 2. This arrangement provides a substantial mounting for the bristles and, because of the resiliency of the legs 35 and 36 of the staple, some flexibility or relative movement between the plastic parts 13 and the core 11 is permitted without damaging the mounting of the bristles. Although the mounting of only one tuft of bristles has been described, it will be understood that a full contingent of tufts of bristles may be mounted on the brush roll in this manner or some other suitable manner.

In the embodiment shown in Fig. 6, a pulley 40 is recessed, as indicated at 41, and the roll members 13 have end portions 42 of reduced diameter which project into the recesses 41. The portions 44 of the roll members serve as guides to prevent a belt from running off the pulley 40. In this embodiment, clearance spaces 42, 43, and 45 are provided between the ends of the roll members 13 and the pulley 40 by shrinking of the roll members 13 in the initial molding of the same. These clearance spaces are hidden from sight by the overlapping edges of the pulley. In all other re-

spects this embodiment is the same as the embodiment previously described.

This invention has been described in connection with a brush roll or rotor for a suction cleaner having a pulley intermediate its ends. However, it is understood that this invention may apply equally as well to any type of brush roll or plain roll or rotor not having a brush thereon, regardless of whether the pulley is intermediate its ends or at one or both ends. This invention also applies equally as well to brush rolls and plain rolls or rotors that are rotated by contact with a surface.

An advantage afforded by this invention is that it provides a fabricated plastic brush roll or rotor having a metallic core wherein the plastic portion of the roll or rotor may expand and contract relative to the core without any appreciable warping or cracking of the plastic portions or the core and without injuring the bond between the plastic portions and the core.

While I have shown my invention in several forms, it will be obvious to those skilled in the art that it is not so limited, but is susceptible of various other changes and modifications without departing from the spirit thereof, and I desire, therefore, that only such limitations shall be placed thereupon as are specifically set forth in the appended claims.

30 What I claim is:

1. In a brush roll or rotor, a metal member, a plastic member encompassing and closely fitting the outside of the metal member, means locking a portion of said plastic member to said metal member, said metal member and said plastic member being free to move relative to each other throughout a portion of their length when they expand or contract unequally.

2. In a brush roll or rotor, a metal member, 40 a pulley on said metal member, a plastic member encompassing and closely fitting the outside of said metal member, said pulley and said plastic member being positioned in end-to-end relation, means adjacent the end of said plastic member 45 farthest from the pulley and locking a portion of said plastic member to said metal member, a portion of said metal member being smooth so that portions of said plastic member may move toward said locking means during contraction of said plastic member and provide a clearance space between the adjacent ends of the plastic member and the pulley so that these portions may subsequently expand and contract unequally without setting up damaging stresses in each other.

3. In a brush roll or rotor, a metal member, a pulley positioned intermediate the ends of said metal member, a plastic member encompassing the metal member on each side of said pulley, and means adjacent one end of each of said plastic members for permanently locking a portion of said plastic members against rotational or axial movement relative to said metal member, the other portions of said metal member and said plastic members being free to move relative to each other and to said pulley when they expand and contract unequally.

4. In a brush roll or rotor, a metal member, a pulley positioned on said metal member, a plastic member encompassing and closely fitting the outside of the metal member, means locking said plastic member to said metal member to prevent it from rotating on said metal member, and means permanently locking a portion of said plastic member against axial movement relative to

said metal member, portions of said metal member and said plastic member being free to move relative to each other when they expand or contract unequally.

5. In a brush roll rotor, a metal member, a pulley positioned on said metal member, said pulley having a recess therein, a plastic member encompassing and closely fitting the outside of said metal member, a portion of said plastic member extending into said recess in said pulley, means locking said plastic member to said metal member at the end of the plastic member remote from said pulley so that when said plastic member contracts a portion of the same will move toward said locking means far enough to move the ends of said plastic member far enough away from said pulley so that said plastic member may subsequently expand without setting up objectional stresses in the brush roll or rotor.

6. In a brush roll or rotor, a metal member, a pulley carried on said metal member intermediate its ends, a plastic roll member encompassing and carried on said metal member on each side of said pulley, said plastic roll members having a larger diameter than said pulley, the inner ends of said plastic roll members forming guards adjacent the ends of said pulley for preventing a belt from running off said pulley, a portion of each of said plastic members being locked against rotational and axial movement relative to said metal member, other portions of said plastic members being free to move axially with respect to said metal member when said plastic member and said metal member expand or contract unequally.

7. In a brush roll or rotor, a metal member, a plastic roll member encompassing said metal member and closely fitting the outer surface thereof, means locking said plastic roll member to said metal member to prevent it from rotating relative to said metal member, comprising grooves formed at one end of said metal member for receiving the material of said plastic roll, and means for mounting said brush roll in the nozzle of the suction cleaner, and means for applying rotary motion to said brush roll.

8. A brush rotor comprising a metal member, a pulley keyed to said metal member intermediate the ends thereof, plastic members on said metal member disposed on the opposite sides of said pulley, and means for locking only the outer end portions of said plastic members to said metal member, the remaining portions of said plastic members being free to move longitudinally with respect to said metal member and said pulley, the inner ends of said plastic members and the juxtaposed ends of said pulley having an overlapping sliding relationship.

9. In a brush roll, an elongated core member having a smooth outer cylindrical surface, an elongated plastic member encompassing said core member and closely fitting said smooth surface, said core member and said plastic member being formed, adjacent one end of the latter, with interlocking portions, whereby said plastic member is locked to the core member adjacent said one end but is free to expand and contract relative to said core member along said smooth surface.
